(57) **CLAIM**

The ornamental design for a serum vial with bear brush, as shown and described.

DESCRIPTION

FIG. 1 is a front elevational view of a serum vial with bear brush, showing our new design;

FIG. 2 is a rear elevational view thereof;

FIG. 3 is a right side elevational view thereof;

FIG. 4 is a left side elevational view thereof;

FIG. 5 is a front perspective view thereof;

FIG. 6 is top plan view thereof;

FIG. 7 is a bottom plan view thereof;

FIG. 8 is an exploded front perspective view thereof

FIG. 9 is an exploded rear perspective view thereof;

FIG. 10 is an enlarged view of the region circled as 10 within FIG. 8;

FIG. 11 is an enlarged view of the region circled as 11 within FIG. 8;

FIG. 12 is an enlarged view of the region circled as 12 within FIG. 9;

FIG. 13 is an enlarged perspective view of the region circled as 13 within FIG. 9;

FIG. 14 is a rear elevational view of FIG. 13;

FIG. 15 is a right side elevational view of FIG. 13;

FIG. 16 is a left side elevational view of FIG. 13;

FIG. 17 is a front elevational view of FIG. 13;

FIG. 18 is a top perspective view of FIG. 13;

FIG. 19 is a top plan view of FIG. 13; and,

FIG. 20 is a bottom plan view of FIG. 13.

The dot-dash lines in the drawings depict symbolic break lines. The symbolic break lines and anything beyond the symbolic break lines form no part of the claimed design.

1 Claim, 20 Drawing Sheets
